UNITED STATES PATENT OFFICE

2,274,472

RAILWAY CAR END CONSTRUCTION

Henry D. Breen and Arthur F. O'Connor, Chicago, Ill., assignors to Union Asbestos & Rubber Company, Chicago, Ill., a corporation of Illinois

Application February 12, 1940, Serial No. 318,432

6 Claims. (Cl. 105—410)

Our invention relates to car body construction and has particular reference to the construction of the ends of the car from metallic sheets, and more particularly to the type of pressed metallic car end which has horizontally extending corrugations and which has been used extensively in freight car construction for many years. It is the object of the invention to provide economical means for strengthening such corrugated metal car ends without adding appreciably to the present overall thickness of the ends.

The conventional metal car end comprises a metal sheet or sheets extending from corner post to corner post of the car, with horizontally extending corrugations formed in the sheets, said corrugations being pressed in the sheets while they are at a red heat. The thickness of the metal in the corrugated portion of the sheet is necessarily thinner than the plane portion of the sheet and the depth of the corrugations is therefore limited to a depth consistent with a predetermined thickness of the metal in the corrugations, based upon the required strength of corrugations having a given thickness of metal. Aside from the consideration of strength it is of great importance that the overall thickness of the corrugated car end be held to a minimum in the interest of economy of space.

It is well known that the end walls of railway cars are subjected to horizontal forces of considerable magnitude due to thrusts and pressures applied thereto during shifting of car lading in a direction longitudinally of the car, caused by buffing and draft shocks received by the car in switching operations and in the general starting and stopping of the cars in train movements. When these thrusts are localized upon the car end adjacent the vertical center thereof it frequently results in the pushing out of the car end and resulting in permanent distortion thereof.

A wooden end lining is usually mounted upon the inner surface of the metal car end to form the inside wall of the car. For many types of lading it is important that this wooden end lining be tight where the lining boards join each other, in order to form a modified form of insulation between the metal car end and the lading. When the cars are used to transport grains or other bulk material any breaks or openings in the wooden lining will result in loss of the lading through the lining. Where cartons or cans of material are loaded in the car they must be prevented from contacting the metal car end due to the condensation of moisture upon the

metal end or the cartons will disintegrate and the cans will rust, causing lowered market value of the commodities or total loss thereof.

Where refrigerator cars are provided with the conventional corrugated metal ends the bulkhead (separating the lading compartment from the ice compartment) in many cases is provided with thrust members which depend upon the metal car end to keep the bulkhead in position.

10 As the bulkhead is subject to the same horizontal forces as the car end in a box car any distortion or resiliency in the metal end results in movement of the bulkhead, longitudinally of the car, and places stress and strain upon supports and bulkhead anchoring members which are not intended to resist such forces, resulting in damage to metal floor pans, metal floors and other parts of the car interior which must be watertight to prevent ice meltage from entering the insulated car walls and floors. Refrigerator car walls and floors invariably have relatively expensive hair or fiber insulation between the inner and outer wall linings which lose their insulating value if they become wet. If the insulation becomes wet it also results in deterioration of same and adds considerable dead weight to the car.

When a corrugated metal car end has been pushed outwardly to a point where it has taken a "set" in the distorted position it is necessary to take the car out of service, place it in a car repair shop or repair yard and force the distorted portion back into place. This results in a weakened end wall, loss of revenue while the car is out of service, expensive repairs in tearing out the damaged lining, insulation, etc., and the replacement of same.

An object of the present invention is to provide means whereby the conventional corrugated metal ends may be strengthened without adding materially to the overall thickness of same.

Another object is to provide strengthening means which may be inexpensively and readily applied to existing car ends to make them serviceable, thereby salvaging car ends which might otherwise have to be scrapped and replaced.

Another object is the provision of strengthening means for corrugated metal car ends which will substantially reduce the span of the corrugations by one half, thereby reducing the possibility of the ends bulging out.

A further object is to provide reinforcing means for metal car ends which will add a minimum amount of additional weight to the ends.

Another object is to provide strengthening

means to the conventional metal car ends by tying the corrugations together, adjacent the vertical center of the car ends, thereby minimizing the possibility of the corrugations bulging as the spacing between corrugations must change before such bulging will occur.

Further objects of the invention will appear hereinafter, in conjunction with the accompanying drawing, in which—

Fig. 1 is a fragmentary end elevation of the end of a car with the reinforcing means shown applied to the car end.

Fig. 2 is a fragmentary sectional view taken along line 2—2 of Fig. 1.

Fig. 3 is a fragmentary horizontal sectional view of the reinforcing means shown in Fig. 1, taken along line 3—3 of Fig. 1.

Fig. 4 is a fragmentary vertical section taken along line 2—2 of Fig. 1, showing a modification of the reinforcing means.

Fig. 5 is a fragmentary elevation of the outer reinforcing member of Fig. 1.

Fig. 5a is a fragmentary side elevation of the outer reinforcing member shown in Fig. 5.

Fig. 6 is a side elevation of one of the reinforcing segments shown in Fig. 4.

Fig. 6a is a plan view of the segment shown in Fig. 6.

Fig. 6b is an end elevational view of the segment shown in Fig. 6.

Referring to the drawing, the reference numeral 13 indicates the roof of the car, 15 the end sill, and 17 the car end of corrugated sheet metal. The car end may be secured to the roof 13 and to the end sill 15 by means of rivets 19 and 21, respectively. The car end 17 may comprise a plurality of metal sheets spliced together in the usual way. The car end 17 may be provided with vertical marginal flanges 23 extending around the corner of the car and affixed to the conventional corner post or to the side wall sheathing in the usual manner.

The reinforcing member 25, as shown best in Fig. 1, may comprise a channel-like member having longitudinal marginal flanges 27 and end flanges 29 and 31.

Flanges 29 and 31 may be secured to the adjacent flanges 27—27 by welding, as indicated at 33, to form a box-like upper and lower end portion on the member 25. The flanges 27—27, intermediate the end portions of member 25, may be provided with a series of inwardly extending arcuate portions 35 and alternate outwardly extending arcuate portions 37, the arcuate portions 35 being spaced coincident with the spacing of the outwardly extending corrugations on the car end 17, the arcuate portions 37 fitting into and substantially registering with the valley portions of the same corrugations.

The reinforcing member 25 may be mounted upon the car end 17 with its portions 35 and 37 in abutting engagement with the outwardly extending corrugations and the intermediate valleys of said corrugations, respectively, and may be affixed to the car end by welding. A reinforcing member 39 may be affixed to the opposite side of the car end 17, in order to complement the member 25 and form a vertically extending box-like reinforcement intersected by the corrugated metal end wall. Member 39 may comprise a plate-like member 41 having scalloped flanges 43 along its opposed longitudinal margins adapted to fit into the valleys of the corrugations and to register substantially with the outwardly extending corrugations (viewing the car

end 17 from the interior of the car). The reinforcing members 25 and 39 may be affixed to the car end as by welding 45 which may be a continuous weld along the margins of flanges 27 and 43 or may be tack welded (spaced apart welds). It will be seen that the box-like reinforcing means provides great strength to resist bulging of the car ends and adds a negligible amount to the original thickness of the car end.

10 The modified reinforcing means shown in Fig. 4 may comprise a vertically aligned series of plate members 47, provided along their vertical margins with arcuate flanges 49 adapted to fit into and register with the contour of the valley portions of the corrugations in the car end 17. The planes of the flanges 49 may extend vertically of the car and perpendicular to the plane of the car end 17. When the members 47 are used on both sides of the corrugated car end they will be in staggered relationship with each other (the members on the inside being staggered with respect to the members on the outside), and the flanges 49 of the inner members are preferably coplanar with the flanges 49 of the outer members. A channel shaped member 51 may be provided intermediate the bottom corrugation and the lower margin of the car end 17, and may be provided with opposed marginal flanges 53 adapted to abut the adjacent portion 20 of the bottom corrugation and the adjacent plane portion of the car end 17, the spaced apart flanges 53 being in coplanar alignment with the spaced apart flanges 49 of member 47. The lower end of member 51 may be provided with a flange 55 intermediate and parallel with the lower ends of flanges 53 and may be welded to form a box-like closed end portion on member 51. The outer surfaces of the members 47 may be in a plane with one or more of the vertical boundaries of the car end 17. A plate-like member 57 may be provided adjacent the top corrugation and may extend from a point near the apices of said corrugation to a point adjacent the upper margin of the car end 17, in oblique relation to the plane of the car end 17. Member 57 may be provided with spaced apart vertical flanges 59 having a peripheral contour adapted to register with the contour of the corrugation and the adjacent plane portion of the car end 17, flanges 59 being coplanar with the flanges 49 of the aligned members 47. A channel-shaped member 61 may be provided intermediate the valley portion of the top corrugation and the adjacent upper margin of the car end 17 and may be provided with spaced apart marginal flanges 63 in alignment with flanges 49 and 59.

Having thus described our invention, what we claim as new and desire to secure by United States Letters Patent, is:

1. An end wall for a railway car comprising a plate provided with a plurality of corrugations, reinforcing means for said wall comprising a plurality of spaced apart plate members in the valley of one of said corrugations, a plurality of spaced apart plate members in the valley next adjacent on the opposite side of said wall, the spaced apart plate members on one side of said wall being in planar alignment with the spaced apart members on the opposite side of said wall, a plate member connecting the spaced apart members in one of the valleys adjacent their outer margins, said spaced apart members extending transversely of said corrugations with their planes perpendicular to the plane of said

wall, the margins of said spaced apart members adjacent said wall being in abutting engagement with and welded to the walls of said corrugations.

2. An end wall for a railway car comprising a sheet metal plate provided with a plurality of corrugations, means for reinforcing said wall comprising a plurality of spaced apart plate members in the valley of one of said corrugations, a plurality of spaced apart plate members in the valley next adjacent on the opposite side of said wall, the spaced apart plate members on one side of said wall being in planar alignment with the spaced apart members on the opposite side of said wall, a plate member connecting the spaced apart members in one of the valleys adjacent their outer margins, said spaced apart members extending transversely of said corrugations with their planes perpendicular to the plane of said wall, the margins of said spaced apart members adjacent said wall being in abutting welded engagement with the walls of said corrugation.

3. An end wall for a railway car comprising a plate of sheet metal having upper and lower marginal plane portions and a plurality of corrugations therebetween, means for reinforcing said wall comprising a hollow elongated member having opposed wall portion, extending transversely of said corrugations and the adjacent plane portions of said wall, the planes of said opposed wall portions being at an angle to the plane of said wall, said elongated member being bisected by said corrugations and said plane portions, with one of the bisections on one side of the wall and the other bisection on the opposite side of the wall, the margins of each bisection adjacent the wall being adapted to substantially dam the valleys of the corrugations and being welded to said wall and said corrugations.

4. An end wall for a railway car comprising a plate provided with a plurality of corrugations, reinforcing means for said wall comprising a box-like elongated member having spaced apart portions extending transversely of said corrugations in a plane parallel to the plane of said wall and spaced apart portions extending perpendicular to the plane of said wall, one of said first named portions being in adjacent overlying relationship with the apices of the corrugations on the outside of the wall, the other of said first named portions being in adjacent overlying relationship with the apices of the corrugations on the inside of said wall, the said portions which extend perpendicular to the plane of said wall

being bisected intermediate their longitudinal margins by said corrugations, the margins of said last named portions adjacent the end wall having edgewise engagement with and being welded to said end wall, the last named portions on the outside of said wall being in planar alignment with the last named portions on the inside of said wall.

5. An end wall for a railway car comprising 10 a plate provided with a plurality of corrugations, reinforcing means for said wall comprising a box-like elongated member comprising a plurality of segments disposed in planar alignment transversely of said corrugations on both sides 15 of said wall, a plurality of said segments on one side of said wall being in staggered relationship with the adjacent segments on the other side of said wall, said segments comprising plate members in parallel relationship with the plane of said wall with their outer surfaces substantially coplanar with the outer surfaces of the apices of the corrugations, said plate members being provided with spaced apart flanges adapted to fit into and substantially dam the valleys of the corrugations, said spaced apart flanges extending in a plane perpendicular to the plane of said wall and having edgewise welded engagement with said wall, the spaced apart flanges on one side of said wall being in planar alignment with the spaced apart flanges on the other side of said wall.

6. A sheet metal end wall for a railway car, said wall having a plurality of substantially parallel elongated corrugations formed therein, reinforcing means for said wall comprising metallic channel-shaped members, one of said members being on the outside of said wall and one of said members being on the inside of said wall, the member on the outside of said wall having spaced apart portions extending into and substantially damming the valley of one of said corrugations, the member on the inside of said wall having spaced apart portions extending into and substantially damming the valley next adjacent to said first named valley, the portions of said members which dam said valleys extending transversely of said corrugations in planes substantially perpendicular to the plane of said wall and being rigidly affixed thereto, the spaced apart portions of the oppositely disposed channel-shaped members being in coplanar alignment respectively.

HENRY D. BREEN.

ARTHUR F. O'CONNOR.
